UNITED STATES PATENT OFFICE.

VIRGIL C. KOONS, OF COLORADO SPRINGS, COLORADO, ASSIGNOR TO THE CONTINENTAL MANUFACTURING COMPANY, OF COLORADO SPRINGS, COLORADO, A CORPORATION OF COLORADO.

CHICKEN-CULTURE APPARATUS.

No. 898,737.

Specification of Letters Patent. Patented July 21, 1908.

Application filed June 26, 1907. Serial No. 380,966.

To all whom it may concern:

Be it known that I, VIRGIL C. KOONS, a citizen of the United States, residing at Colorado Springs, El Paso county, Colorado, have invented certain new and useful Improvements in Chicken-Culture Apparatus; and I do hereby declare the following to be a full, clear, and exact description of the invention, such as will enable others skilled in the art to which it appertains to make and use the same.

This invention relates to certain improvements in chicken culture apparatus, and more particularly relates to improvements in chicken brooders; and the objects and nature of my invention will be readily understood by those skilled in the art in the light of the following explanation of the construction shown in the accompanying drawings 20 as my preferred embodiment from among other structures within the spirit and scope of my invention.

The invention consists in certain novel features in construction of parts and details and 25 in arrangements and combinations of elements as more fully and particularly set forth hereinafter.

Referring to the accompanying drawings:—Figure 1, is a vertical cross sectional view through a stationary or colony brooder, dotted lines showing the cover screens for the inside runways in raised position. Fig. 2, is a horizontal section on the line 2—2, Fig. 1. Fig. 3, is a cross sectional view on 35 an enlarged scale. Fig. 4, is a cross section, showing a modified arrangement, the wall carrying the heating flues being shown swung outwardly. Fig. 5, is a section taken on the line 5—5, Fig. 3. Fig. 6, is a section taken 40 on the line 6—6, Fig. 3. Fig. 7, is a section taken on the line 7—7, Fig. 3. Fig. 8, is a section taken on the line 8—8, Fig. 4.

In the specific example illustrated, I show what might be termed, a colony brooder, 45 wherein a number of apartments are provided whereby the chicks can be separated into broods according to age and the different broods can be kept separated, or if so desired, the different compartments or brooding chambers can be thrown into communication with each other when the chicks arrive at such age as to permit intermingling of the different broods.

The brooder shown can be used as a stationary brooder and located in a suitable

building on the floor of which the chicks can run from each brooder apartment. When the brooder is thus employed as a stationary brooder, I usually, provide separate runways on the floor of the building, for each brooder apartment, each apartment having a door in its front wall through which the chicks can pass to and from the apartment.

In the specific example illustrated, I show a removable brooder capable of being moved from the building and placed out of doors, and when so used, I preferably provide a removable roof, cap or cover for the brooder, to protect the brooder apartments from the direct rays of the sun and from the cold and 70 weather.

In the drawings, I show the brooder removably resting on the ground or on the floor of a building, with its rear wall adjacent to a depressed alley or passage way 1, in 75 which the operator can freely move when inspecting brooder and chicks and attending to the heating apparatus, etc.

The brooder is suitably constructed with a strong framework secured to and rising from a horizontal main floor 2, preferably extending throughout the length and width of the brooder.

The heating chamber is preferably arranged throughout the length of the rear side 35 of the brooder and is closed at its rear side by the rear vertical wall of the brooder and is preferably closed at its bottom by said floor 2, on which the heater, such as a heating lamp 3, removably rests at one end of the 90 heating chamber.

The brooding apartment or apartments 4, are arranged beside or in front of the heating chamber and are separated therefrom by the vertical wall 5, extending longitudinally 95 throughout the length of the brooder and forming the front longitudinal wall of the heating chamber. At the top, the heating chamber is closed by the preferably fixed horizontal top wall 6, extending longitudinally throughout the length of the brooder, while the rear vertical longitudinal wall 7, of the brooder forms the longitudinal outer wall of the heating chamber, and extends from the top wall 6, to the rear edge of the main floor 2, and the end walls of the brooder close and form the end walls of the heating chamber.

Various means can be employed to heat the air within the heating chamber for dis- 110

tribution to the brooding apartments. For example, I show sheet metal heating flues arranged longitudinally within the heating chamber to receive the heat and products of combustion from the lamp. Such flues can consist of the horizontally elongated main drum or flue 8, extending approximately throughout the length of the heating chamber, and the return flue or drum 9, arranged longitudinally on the main flue 8, approximately throughout the length thereof and at one end opening at 8^a into the main flue opposite the lamp receiving end thereof. At one end the main flue is formed with an opening in its bottom to receive the vertical, usually metal chimney 10, of the removable lamp 3, and through which the products of combustion and heat from the lamp are discharged vertically into said main flue and against the top wall thereof so that the heat and products of combustion pass throughout the length of the main flue and then up into the return flue and throughout the length thereof and out through the vertical discharge 11, extending through the top wall of the heating chamber to the exterior thereof, and extending up from the end of the return flue directly over the lamp so that the direct upwardly flowing heat of the lamp will maintain an upward draft through said discharge and thereby maintain a draft through said flues.

The chimney is preferably vertically movable independently of the lamp so that the chimney can be raised to permit removal of the lamp for filling or other purposes. I hence usually support the chimney independently of the lamp, as by lever 12, secured to the main flue and arranged at the under side thereof and pivotally joined to the chimney to support the same when the lamp is removed and by which the chimney can be raised from the lamp burner.

The heating flues are arranged a distance above the floor of the heating chamber and are spaced from the side and top walls thereof to permit circulation of air in the chamber completely around the heating flues. The heating flues are preferably carried by and secured to the longitudinal rear wall 7, of the brooder, as by supporting brackets 13, secured to the flues and to the inner face of said wall. I preferably hinge said wall 7, at its upper edge at 7^a to the outer edge of the top wall 6, to permit outward and upward swing of said wall, thereby carrying the heating flues outwardly and upwardly from the heating chamber and exposing the ends of said flues. The flues are preferably provided with or are closed by removable end caps 14, which can be removed when the flues are moved outwardly from the heating chamber as just described, to permit the insertion of a cleaning brush into the flues for removal of soot or other deposits therein.

The vertical discharge pipe 11, is preferably removably fitted into the top of the return flue, to permit removal of said pipe when the flues are to be carried outwardly by the wall 7, for cleaning or examination. The lamp also is removed before said wall is swung outwardly. Access to the lamp is gained through an opening in the rear wall 7, through which opening said lamp can also be inserted and removed, and this opening is normally closed by a suitable movable door 15. The rear wall 7, is also provided with fresh air openings 16; and a series of these openings 16, are usually employed spaced a distance apart and opening through the lower portion of the wall to deliver fresh air into the heating chamber below the heating flues so that the fresh air will be heated by the flues before passing from the heating chamber into the brooding apartment or apartments through heated air escape openings 17, in the upper portion of the inner side wall 5, separating the heating chamber from the brooding chamber.

I usually employ a series of the openings 17, through wall 7, arranged throughout the length of said wall to distribute the heated air therethrough into the brooding chamber whether said chamber forms a single apartment or is subdivided into a number of apartments. In the specific example illustrated, I show the brooding chamber divided into three separate apartments by transverse parallel vertical partitions 18, each extending the full width and height of the brooding chamber. Where the brooding chamber is thus divided into apartments, I preferably provide one or more heated air inlets 17, into the upper portion of the rear or inner end thereof, and these inlets 17, preferably are covered by wire netting 19, or the like, to permit passage of the heated air and yet prevent the chicks passing through the openings into the heating chamber. I also preferably provide means whereby the passage of heated air into any brooding apartment can be separately controlled, independently of the flow of heated air into the remaining apartments. For instance, I show a sliding damper 20, for each opening 17, arranged at the front side of wall 5, and slidably under the turned back edges of a metal plate 21, secured to said wall, although I do not wish to limit myself to such specific arrangement. By means of these slides or dampers 20, any one or several of the heated air passages 17, can be closed. I can also provide openings in the partitions 18, for the passage of chicks from one apartment to the next, and suitable doors, such as slides 22, are provided for closing these openings. The front wall 23 of the brooder is also provided with openings into the respective brooding apartments for the passage of chicks to and from said apartments and outside runways, and these open-

ings are provided with suitable doors, such as slides 24.

The brooding chamber is provided with a false or elevated floor 25, extending from the wall 5, to the front wall 23, and throughout the length of the brooding chamber and apartments formed therein. This brooder chamber floor 25, is supported on and spaced from the main floor 2, by suitable transverse strips or cleats 26, each strip being usually arranged about in the plane of, that is, beneath, a partition 18, so that an air space or passage will be provided under such brooding apartment. These air spaces at their rear ends open beneath the wall 5, into the lower portion of the heating chamber below the heating flues therein.

At its front side, each brooding apartment is provided with a vertical down draft air flue 27, at its lower end opening into said air space between the two floors and at its upper end opening into the upper part of the interior of the brooding apartment. Each air flue 27, can be formed by a U-shaped or longitudinally dished length or strip of sheet metal secured vertically along its opposite edges to the inner surface of the front wall 23, with the upper end of the channel or flue thus formed open near the top of the apartment and the lower end registering with a vertical hole through the floor 25.

To provide ventilation in the brooding apartments and to carry off vitiated or foul air, I can form holes 28, through the upper part of the front wall 23, opening into the outer air, and adapted to be closed and opened by exterior caps, such as 29. I can provide one of these outlets 28, for each brooding apartment, and within the apartments, I can secure dished pieces of metal 30, to the inner surface of the front wall 23 to form vertical flues at their upper ends closed within the apartments but discharging through said holes and opening at their lower ends into the lower portions of the apartments so that the foul air can rise through said flues and pass out through said holes without creating an injurious draft of cold air in an apartment.

The upward movement of air in the heating chamber creates a rearward draft into said chamber through the air spaces between the double floor and hence draws air from the upper front portions of the brooding apartments through down flues 27, into said air spaces, thereby maintaining a constant circulation of heated air through the brooding apartments, and the desired uniform heating, as the heated air from the heating chamber flows into the rear ends of said apartments through the inlets 17.

If so desired, to cause downward distribution of heated air in the brooding apartments and to provide a rear possibly somewhat warmer inclosure within each brooding apartment, I can arrange a loose flexible

hanging curtain 31, of suitable fabric about midway between the front and rear walls of each brooding apartment, and interposed directly between the heated air inlets and the down take outlets. These curtains at 70 their upper edges can be secured to any suitable support arranged along the tops of the brooder apartments and hang almost to the floor 25, causing the heated air in each apartment to flow to the floor to pass under the 75 curtain. The chicks can easily pass under the curtain and in cool weather or when very young may find the temperature more comfortable in rear of the curtain than in front thereof, although by reason of my system for 80 maintaining heated air circulation, I find that the temperature is approximately uniform throughout each apartment. However, I do not wish to limit all features of my invention to employment in connection with such depending curtains.

The upward flow of air in the heating chamber and around the heating flues therein, will cause the inflow of the required quantity of cool or fresh air through the fresh air inlets 16, and this fresh air mingles with the heated air and becomes heated before passing into the brooding apartments.

I do not, as at present advised, by practical use of my invention, wish to limit myself strictly to forming the return air passages from the brooding chamber to the heating chamber, by the double floors, as other means or arrangements might be provided for producing such return air passages. 95 Furthermore, I do not wish to limit myself to the ventilating system disclosed for permitting escape of vitiated air from the brooding apartments, nor to the formation of a number of brooding apartments, although my invention is particularly applicable to employment in connection with colony brooders employing a number of separate brooding apartments.

The top wall of the brooding chamber is 110 preferably formed with upwardly swingable hinged covers or doors 32, one for each brooding apartment, and each cover can consist of a glazed sash, that is a sash with glass panes or panels, to provide for ample light in each apartment. Where the brooder is to be set up and operated out of doors, that is, not in a chicken house or building, I 115 preferably provide a removable roof or cap 120 33 therefor which removably rests on and covers the brooder and forms a dead air space above the same see Figs. 4 and 8. The cap can be removably secured on the brooder by suitable means, such as hooks and eyes 125 34, as shown. The specific example of cap shown, comprises a vertical front wall having glass panels or panes inserted therein to permit access of light to the brooding apartments, and a downwardly and rearwardly inclined top wall or roof extending to the 130

4
rear edge or portion of the heating chamber of the brooder. This top wall or roof can be provided with hinged doors 35, adapted to swing vertically and permit access to the 5 hinged sashes closing the tops of the brooder apartments, I can provide a door 35, over each brooder apartment so that when a door 35 is opened, the sash 32, below the same can be opened and will swing up through the 10 opening in the cap roof normally closed by a door 35.

Where the brooder is employed as a stationary brooder, within a chicken house or building 36, it is not necessary to use a cap 15 33. When the brooder is arranged within a building 36, I usually provide a separate chick runway for each brooder apartment and arrange these runways between the front wall of the building and the front wall 20 of the brooder and along the floor of the building. These runways can be formed by vertically removable partitions 37, spaced the required distance apart and from the end walls of the building and fitting at their ends 25 between vertical sockets formed by cleats 38, secured at the front wall of the brooder and at the inner side of the front wall of the building.

Openings can be provided through the 30 front wall of the building into each runway, and through which the chicks can pass to runways at the exterior of the building. Vertically movable drop doors or slides 39, can be provided for closing said openings. 35 Cords 40, can be provided for controlling these slides. These cords are shown running through supports 41, within the building by which they are carried to the rear wall of the building within easy reach of the 40 operator in the depressed aisle or passage 1, so that the operator standing in said depressed passage can operate said cords to raise or lower any slide.

I preferably provide means for covering 45 the runways within the building to prevent the chicks jumping over the partitions 37. For instance, I show screen or netting covered frames 42, normally arranged in horizontal positions over and covering the runways, one screen for each runway. I usually 50 hinge these screens at their rear ends, at 43, to the top of the brooder so that the screens will extend to the front wall of the building and rest on the upper edges of the removable 55 partitions 37. By thus hinging the screens, they can be swung to the vertical position to uncover the runways and form a partition the length of the building and prevent the chicks jumping on or passing rearwardly 60 over the brooder. The screens can be held in the vertical position by swinging depending latches or stops 44, hinged to and depending from the top or roof of the building about as shown.

65 If so desired, cords 45, can be provided to

raise the cover screens 42, the same as the cords 40, are arranged to raise the drop doors 39. The cords can extend from the rear wall of the brooder housing, inclosure or building, accessible from the depressed passage, through eyes or other suitable supports to the free ends of the cover screens. 70

It is evident that various changes and modifications might be resorted to, that elements might be omitted and features and structures added, without departing from the spirit and scope of my invention, and hence I do not wish to limit myself to the exact constructions shown but consider myself entitled to all such changes as fall within the 80 spirit and scope of my invention.

What I claim is:—

1. In combination, in a brooder housing having a floor, a brooder arranged in said housing along the floor thereof and formed 85 with brooder apartments each having an outlet opening for the passage of chicks, runways formed along said floor, one for each brooder apartment, removable partitions between said runways, and movable screens 90 covering said runways.

2. In a brooder housing having a floor, a brooder arranged horizontally therein, a chick runway arranged along said floor, a vertically swinging screen adapted to cover 95 the runway, and means for holding the screen in a vertical position when swung up from the runway.

3. In a brooder housing having vertical inclosing walls and a floor formed with a depressed passage way, a brooder arranged on said floor in front of said passage way and closely adjacent thereto, partitions between the front of the brooder and the front wall of said housing forming separated chick runways, removable means to cover said runways, said front wall of the housing having chick passage openings into said runways, doors for closing said passage openings, and means for controlling said doors extending to 100 and manually operated from points adjacent to and accessible from said depressed passage way.

4. A brooder having a longitudinal heating chamber and means for heating the same, 115 a brooding chamber beside said heating chamber, series of partitions subdividing the brooding chamber and having openings therethrough and means for closing the same, means for supplying heated air from said 120 heating chamber into said sub divisions, removable partitions at the exterior of the brooding chamber and forming series of runways, each brooding chamber having a passage way to a runway and means for closing 125 the same, and vertically swingable cover screens for said runways, substantially as described.

5. In a brooder housing having a floor and vertical inclosing walls and a passage way 130

spaced from the front wall of said housing, a brooder arranged between said passage way and front wall and having a heating chamber and a brooding chamber, run ways between said brooding chamber and said front wall, vertically swingable cover screens over said runways, and lifting cords for said cover screens extending to points accessible from said passage way.

10 6. A brooder having a brooder chamber, a heating chamber arranged longitudinally of the brooder and at one side of the brooder chamber and communicating therewith to supply heated air thereto, heating flues in closed longitudinally within said heating chamber, said flues being provided with removable end caps, said brooder having a movable wall, said flues being secured to and movable with said wall, whereby said caps can be exposed and removed to permit cleaning the flues by moving said wall to carry the flues from the heating chamber.

7. A brooder having a brooder chamber arranged longitudinally thereof, a heating chamber arranged longitudinally thereof and communicating with the brooder chamber to supply heated air thereto, a wall of said brooder being provided with fresh air inlets into said heating chamber, heating flues in said heating chamber, and a return draft flue from the brooder chamber to the heating chamber and opening into the upper portion of the brooder chamber and into the lower portion of the heating chamber below the heating flues therein.

8. A brooder having a brooder chamber, and a heating chamber having heating means and communicating with and supplying heated air to the brooder chamber, said brooder provided with a return air passage receiving air from the upper portion of the brooder chamber and returning the same to the lower portion of the heating chamber.

9. A brooder having a brooder chamber, a heating chamber provided with air heating means and communicating with and adapted to deliver heated air into the brooder chamber and provided with a fresh air inlet, said brooder chamber provided with a vitiated air outlet from its lower portion, and an air return flue from the upper portion of the brooder chamber to the heating chamber.

10. A brooder provided with means for heating air and delivering the same into the upper portion of the brooder chamber, said brooder chamber having a heated air outlet from its upper portion, and a flexible curtain depending in the brooder chamber between the heated air inlet and said outlet, substantially as described.

11. A brooder having a main floor, a heating chamber closed at the bottom by said main floor, and provided with heating means, a brooder chamber provided with a false bottom or floor forming an air space above the

main floor communicating with said heating chamber, said heating chamber provided with means for delivering heated air from the heating chamber into the brooder chamber, and a down draft flue from the brooder chamber discharging into said air space.

12. A brooder comprising an inclosure having a longitudinal horizontal heating chamber, a brooder chamber, arranged beside the heating chamber and supplied with heated air therefrom, a longitudinal vertical side wall of said heating chamber being movable to open the heating chamber approximately throughout its length, a horizontally disposed heating flue arranged longitudinally within the heating chamber and spaced from the walls thereof to provide air spaces around the same, means securing said flue to said movable side wall, and a heating burner within said heating chamber to heat said flue.

13. A brooder comprising side, end, top and bottom walls and having a brooder chamber and a longitudinal heating chamber therein and entirely inclosed by said walls, a longitudinal partition separating the heating chamber from the brooder chamber and having openings for the passage of heated air from the heating chamber to the brooding chamber, a horizontal heating flue arranged longitudinally in and entirely inclosed by the walls of the heating chamber, means securing said flue in and spaced from the walls of said heating chamber, and a heating lamp arranged within said heating chamber for heating said flue.

14. A brooder having a brooder chamber and a heating chamber arranged horizontally beside the same, a longitudinal partition separating the heating chamber from the brooder chamber and having series of openings therethrough to admit heated air to the brooder chamber, a heating flue in the heating chamber separated from the walls of the heating chamber to provide air spaces around the flue, means for heating the flue, a return air passage being provided from the portion of the brooder chamber opposite said openings to and discharging into said heating chamber.

15. A brooder having an inclosed brooder chamber having a floor, and a heating chamber arranged beside the brooder chamber and provided with means for heating air therein, heated air being supplied from the heating chamber to the brooding chamber, a return air passage being provided from one side of the brooding chamber to the lower portion of the heating chamber comprising an air space beneath said floor.

In testimony whereof I affix my signature, in presence of two witnesses.

VIRGIL C. KOONS.
